US0D1096771S

(12) **United States Design Patent** (10) Patent No.: **US D1,096,771 S**
 Wang (45) Date of Patent: ** Oct. 7, 2025

(54) **DISPLAY SCREEN WITH GRAPHICAL USER INTERFACE FOR REFRIGERATOR MANAGEMENT**

(71) Applicants: **QINGDAO HAIER REFRIGERATOR CO., LTD.**,
 Qingdao (CN); **HAIER SMART HOME CO., LTD.**, Qingdao (CN)

(72) Inventor: **Yan Wang**, Qingdao (CN)

(73) Assignees: **QINGDAO HAIER REFRIGERATOR CO., LTD.**,
 Qingdao (CN); **HAIER SMART HOME CO., LTD.**, Qingdao (CN)

(**) Term: **15 Years**

(21) Appl. No.: **29/863,868**

(22) Filed: **Dec. 22, 2022**

(30) **Foreign Application Priority Data**

Jun. 28, 2022 (CN) 202230402142.6

(51) **LOC (15) Cl.** **14-04**

(52) **U.S. Cl.**

USPC **D14/488**; D14/486

(58) **Field of Classification Search**

USPC ..... D14/485—495

CPC F25D 2400/361

See application file for complete search history.
